(57) **CLAIM**

The ornamental design for a cane with seat, as shown and described.

DESCRIPTION

FIG. 1 is a front, left, top perspective view of a cane with seat, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left, top perspective view of the cane with seat in the first folding state;

FIG. 10 is a rear, right, bottom perspective view of the cane with seat in the first folding state;

FIG. 11 is a front, left, top perspective view of the cane with seat in the second folding state;

FIG. 12 is a rear, right, bottom perspective view of the cane with seat in the second folding state;

FIG. 13 is a partial enlarged view of FIG. 1;

FIG. 14 is a partial enlarged view of FIG. 1;

FIG. 15 is a partial enlarged view of FIG. 2;

FIG. 16 is a partial enlarged view of FIG. 3;

FIG. 17 is a partial enlarged view of FIG. 3;

FIG. 18 is a partial enlarged view of FIG. 4;

FIG. 19 is a partial enlarged view of FIG. 5; and,

FIG. 20 is a partial enlarged view of FIG. 5.

The dashed broken lines in the figures are for the purposes of illustrating portions of the cane with seat and form no part of the claimed design.

The dash-dot-dash broken lines are for notating enlarged views and form no part of the claimed design.

1 Claim, 20 Drawing Sheets
